UNITED STATES PATENT OFFICE

BENJAMIN FLEIGEL, OF CLEVELAND, OHIO, ASSIGNOR, BY DIRECT AND MESNE ASSIGNMENTS, TO JACK SIMON AND SIDNEY I. GLUECK, OF CLEVELAND, OHIO

TELEPHONE AND DESK MEMO DEVICE

Application filed May 26, 1928. Serial No. 280,698.

This invention relates to a writing tablet, more particularly to a tablet adapted for use in conjunction with a desk telephone or as a tablet complete in itself. The objects of the invention are to generally improve and simplify that type of telephone attachment, in which a roll of paper is carried and adapted to be drawn over a support or table with means for severing a portion of paper having memorandum notations thereon.

A further object is to provide a telephone writing tablet adapted for attachment either to a telephone, to a desk stand or wall of a telephone booth. A further object is to provide means for holding the paper rigid while notations are being made on the same.

My invention is hereinafter more fully described in connection with the embodiment shown in the drawings, and the essential novel characteristics set out in the claims.

In the drawings Fig. 1 is a side elevation of my device mounted on a desk stand; Fig. 2 is a plan of the same; Fig. 3 is a longitudinal cross-section taken along the lines 3-3 of Fig. 2; Fig. 4 is a cross-section taken along the lines 4-4 of Fig. 3; Fig. 5 is a side elevation of my device attached to a telephone; Fig. 6 is a bottom plan of the device shown in Fig. 5; Fig. 7 is a cross section taken along the lines 7-7 of Fig. 6; Fig. 8 is a side elevation of my device mounted on the wall; Fig. 9 is a centrally located longitudinal section of the device shown in Fig. 8; Fig. 10 is a bottom plan of a modified form of the device shown in Fig. 6; Fig. 11 is a cross section located along the lines 11-11 of Fig. 10; Fig. 12 is a bottom plan of the device similar to Fig. 10 but showing an alternate means for clamping the device to a telephone.

In the embodiment shown in the drawings, the attachment proper is preferably stamped from a sheet of suitable metal, comprising a desk or paper supporting portion 15 having at opposite sides thereof depending flanges 16, said flanges extending beyond the forward end of the desk portion to provide curved arms 17. These are formed at their

outer ends with openings to receive a paper roll spindle 18, having a head at one end and a binding nut at the other as shown in Figs. 2, 10 and 12. This spindle carries a tubular spacing member 18a.

The desk portion 15 of the tablet has a pair of transverse slits or incisions formed therein. The metal is forced upwardly into a plane above the upper surface of the desk portion as at 19 and 19', thus providing a pair of transversely extending channels beneath which a strip of paper may be inserted.

The paper roll 20 is loosely mounted on the spindle member 18a. The paper is drawn from the lower portion of the roll over a guide portion or lip 22 of the paper supporting desk 15 and beneath the raised portion 19 over the body of the supporting desk and rearwardly beneath the raised portion 19'. The guide portion or lip 22 appearing in Figs. 3, 6, 9, 10 and 12, it will be noted particularly in Fig. 6, is integral with the top plate or supporting desk 15. It is turned downwardly at an angle approximately co-incident with the angle of the paper strip when the roll is full, and is turned to form a rounded corner as it joins the desk portion, and as seen in Fig. 6 is provided with edge flanges laterally guiding the paper strip.

To prevent the paper from moving during the writing operations, the supporting device 15 is provided with wood blocks 25 which may be held in place by bolts extending through the blocks and flanges 16, or which may be held, as shown in Fig. 7, by inwardly projecting lugs 26. Spring clips 27 and 28 which bear against the paper directly beneath the raised portions 19 of the supporting device 15, are fastened to the wood blocks 25 by screws or any other suitable means.

As shown in Fig. 1, the supporting desk 15 with its roll of paper is mounted on a stand 30 by means of bolts 32 and 33, which pass through the flanges 16 of the supporting device and the side members 35 of the stand.

In Fig. 5 the supporting desk 15 is shown mounted on a telephone. In this instance

bolts 32 and 33 are removed and a U-bolt 40 substituted therefor which acts to clamp the device to the pedestal A of the telephone. A depending lug 42 on the paper supporting desk, and one of the side flanges 16 engage the base B of the telephone to provide a rigid support, which holds the desk at an angle to facilitate making memoranda thereon.

In Fig. 12 another modification of a clamping device is shown. In this form a metal bar supporting member 55 is fastened to one of the blocks 25 and projects outwardly from the desk portion 15 to carry a clamping band 56 which clamps the device to the telephone.

I have shown in Fig. 6 the device mounted on a wall such as may be desired where a telephone booth is used. In this instance the stand 30 is secured to the wall by means of screws 58. In this form, I show a modification of the supporting members for the springs 27 and 28 which constitute a U-shaped bracket member 60, having ears 61, to which are fastened the springs 27 and 28. This U-shaped member 60 is fastened to the base of the stand 30 by means of screws 62.

I find it useful to provide means for supporting a pencil on the device and to this end I use a conically wound spring 65 which is fastened at its vertex by looping the wire around the bolt 33.

In Fig. 12 I have shown metal bracket members 61 which may be substituted for the wooden blocks 25, in which case the springs 27 and 28 as well as the telephone clamp member 55 are bolted or otherwise fastened to these metal reinforcing brackets.

From the foregoing description it will be seen that I have provided a simple telephone writing tablet which may be readily supported either by the telephone itself, on the wall or may be provided with a stand for use on a table. I have also provided means whereby the paper is prevented from movement due to the pressure thereon caused by the writing operations.

I claim:

1. A paper supporting device comprising a sheet metal top member having upstruck portions at its opposite ends and downwardly extending flanges at its opposite sides continued rearwardly to form a support for a roll of paper, the strip of paper from the roll being adapted to underlie the upstruck portions and overlie the intermediate portions of the top, a base beneath said top member in overlapping relation to said flanges, transverse reinforcing means carried by the base, and sheet spring members carried by the reinforcing means and arranged to engage the paper beneath said upstruck portions.

2. A paper supporting device comprising a sheet metal member having side flanges, said member intermediate of the flanges adapted to support a strip of paper, there being upstruck portions of the sheet metal ar-

ranged to overlie the paper while so supported, each of said flanges having elongated continuations, the continuations having openings for receiving a pin for carrying the roll of paper, metal reinforcing members, having end flanges engaging the aforesaid side flanges, spring members carried by the reinforcing members intermediate of the end flanges, and adapted to engage the underside of the paper beneath the upstruck portions.

3. A paper supporting device comprising a sheet metal top member having upstruck portions at its opposite ends and downwardly extending flanges at its opposite sides continued in one direction to form a support for a roll of paper, the strip of paper from the roll being adapted to underlie the upstruck portions and overlie the intermediate portions of the top, a paper guide member integral with the metal top member sloping downwardly toward the paper roll at an angle co-incident with the slope of the paper when the roll is full, and having at each lateral edge upturned lips or flanges to guide the paper strip transversely as it comes onto the metal top, transverse reinforcing means carried by the base and sheet spring members carried by the reinforcing means and arranged to engage the paper beneath said upstruck portions.

In testimony whereof, I hereunto affix my signature.

BENJAMIN FLEIGEL.
